DESIGN FOR A CONTAINER FOR PERFUME
BOTTLES OR THE LIKE

Georges Baud, Paris, France

Application March 29, 1946, Serial No. 128,050
In France January 19, 1946

Term of patent 14 years

(Cl. D58—11)

To all whom it may concern:

Be it known that I, Georges Baud, a citizen of France, residing in Paris, France, have invented a new, original, and ornamental Design for a Container for Perfume Bottles or the like, of which the following is a specification, reference being had to the accompanying drawing, forming part thereof.

Fig. 1 is a front perspective view of the container in closed position, showing my new design;

Fig. 2 is a perspective view of the container in open position.

The back of the container for perfume bottles or the like, is substantially like the front shown.

I claim:

The ornamental design for a container for perfume bottles or the like, as shown and described.

G. BAUD.
